Primary Examiner—Doris V. Coles
Attorney, Agent, or Firm—Banner & Witcoff, Ltd.[57] **CLAIM**

The ornamental design for a portion of a bottom surface of a shoe outsole, as shown and described.

DESCRIPTION

FIG. 1 is a perspective view of a portion of a bottom surface of a shoe outsole showing our new design; FIG. 2 is a bottom plan view thereof;

FIG. 3 is a profile view taken along the line 3—3 of FIG. 2; FIG. 4 is a profile view taken along the line 4—4 of FIG. 2; FIG. 5 is a profile view taken along the line 5—5 of FIG. 2; and,

FIG. 6 is a profile view taken along the line 6—6 of FIG. 2. The broken line showing of a shoe upper and the remaining portion of the shoe sole in FIGS. 1 and 2 is for illustrative purposes only and forms no part of the claimed design.
